CLAIM

The ornamental design of a clothing hanger adapter, as shown and described.

DESCRIPTION

FIG. 1 is a perspective view of a clothing hanger adapter in a reduced scale, showing my new design;

FIG. 2 is a top plan view thereof;

FIG. 3 is a front elevation view thereof, it being understood that the opposite side is a mirror image thereof;

FIG. 4 is one end elevation view thereof, it being understood that the opposite side is a mirror image thereof; and,

FIG. 5 is a bottom plan view thereof.

The ribs on upper surface in FIGS. 1, 2, 3 and 4, and the conventional clothing hanger in FIG. 1 shown in broken lines are for illustrative purposes only and form no part of the claimed design.
